UNITED STATES PATENT OFFICE.

THOMAS JOSEPH MACLAUGHLIN, OF OTTAWA, ONTARIO, CANADA.

GRAIN-DOOR FOR FREIGHT-CARS.

No. 893,001.

Specification of Letters Patent.

Patented July 14, 1908.

Application filed March 15, 1907. Serial No. 362,568.

To all whom it may concern:

Be it known that I, THOMAS JOSEPH MACLAUGHLIN, a citizen of the Dominion of Canada, residing at Ottawa, in the county of 5 Carleton and Province of Ontario, Canada, civil servant, having invented certain new and useful Improvements in Grain-Doors for Freight-Cars, do hereby declare that the following is a full, clear, and exact description 10 of the same.

My invention relates to improvements in grain-doors and the objects of my improvements are to provide inexpensive and safe means of preventing the leakage of grain and 15 such commodities from cars in transit, to facilitate loading and unloading and to obviate the necessity of nailing doors, or the lumber used as temporary doors, to the door-posts and thus prevent damage to doors, lumber 20 and cars. I attain these objects by the mechanism and in the manner illustrated in the accompanying drawings.

Figure 1 is an outside view of the door closed; Fig. 2 is the same from the inside of 25 the car; Figs. 3, 4, and 7 are horizontal sections (Fig. 3 at x—x) Fig. 5 is a vertical section and Fig. 6 is a cross-section of a car showing the door swung up and fastened to the ceiling.

30 Similar letters refer to similar parts throughout the several views.

The door may be in one or more sections, preferably in two, and the sections may be hinged to each other or left separate. The 35 principal object is to readily open the door from the outside of the car without any of the difficulties now attending that operation.

To attain the objects in view, the supplementary door-post A, of soft wood, about 40 1½" thick, is securely screwed to the permanent door-post A', and extends to the highest grain-level of the car, as shown in the several figures. Cleat B, against which one end of the door rests, is temporarily nailed to A, and 45 the other end of the door rests against the inside of the opposite door-post. To prevent the door from moving to the right or left of the opening, cleats C C, are placed against each end of the door and fastened to the inside 50 of the door-posts. These together with cleat B, form a recess into which the door closely fits. To hold the door tightly in place until the grain comes against it, nails G G, are driven into the soft wood diagonally, 55 close to and the heads bent down tightly against the ends of the door, one near the bot-

tom and one near the top at each end of the door, see Fig. 4.

In opening the door, cleat B is pried off by inserting the point of a bar or any pointed instrument, between A and B, at the point V, where a slot or notch is made on the inner edge of cleat B, to facilitate the operation. As soon as cleat B, is pried off the door is forced open by the weight of grain, as shown 65 by dotted lines Figs. 3, 4, and 7. If the bottom of the door should stick against the door plate F, the door can easily be pried up and over the plate by placing the point of a pinch bar under the end of one of the battens E, 70 and this should be done before prying B off.

The object of the supplementary, soft wooden post A, is that the nails which hold the cleat B, to it may be easily withdrawn in 75 prying off cleat B.

The door is made reversible so that any set spring which it may sustain through pressure may be taken out by putting it on the other way. For this reason and in order that a batten may always be on the outside by 80 which the door may be pried up and over the door plate without injury to the door, two battens are placed on one side and one on the other, space being left at the end of each for the insertion of a bar underneath it. 85

Where the door plate F, is narrow enough to allow of the door being brought within the wall space, so that it will not project beyond the inside wall-line, the arrangement shown by Fig. 4 may be adopted, in which the supplementary post A, and cleat B, are used on both of the door-posts A', thus doing away with the necessity of stops C C, in such cases. 90

The door may be securely attached to the car, as shown in Figs. 1 and 6. The iron bar 95 or rod H, is fastened to the beam over the door-opening, at point I, in such a way as to swing outwardly and inwardly, and is fastened to the door by means of the iron ring J. This ring is bolted to the upper edge of 100 the door, through the center batten, and is large enough to allow the rod H, to run readily through it, but too small to admit of the passage of the ring K, on the lower end of the rod H. The door is thus secured to the rod 105 H, and can only be removed from the car by unscrewing the rod from the beam at point I, or by taking ring J, from the door. In hanging the door up when not in use, the rod H, passes through the ring J, as the door is 110 raised and when the upper side edge of the door reaches the beam over the door-opening,

the ring K, at the end of rod H, will project beyond or below the lower side or edge of the door; the rod is then lifted to and hung on the iron hook L, at the ceiling, the door resting on rod H, as shown in Fig. 6. This arrangement does not interfere with the free action of the door in any direction, and the door cannot be injured or knocked off the hook by any jolting or shunting of the car.

10 Separate boards may be used as shown by Fig. 7; one end of each being lightly nailed to cleat B, and the other to the supplementary post A, on the opposite door-post. In this case only one of the stops C, will be required 15 and cleat B. may be sacrificed at each unloading, but the entire door will be saved from injury and opened as readily as if in one piece.

What I claim as my invention, and desire 20 to secure by Letters Patent, is:—

1. In a car door structure, the combination with the door-way, and beam at the top thereof, of a door, a ring thereon, a rod pivoted at substantially the center of the beam, 25 and extending through the ring and means on the car roof for locking the extremity of the rod thereto.

2. In a car door structure, the combination with the car having a door way therein 30 and permanent door posts at the side thereof, of a supplemental door post of relatively soft material secured thereto, a door slightly greater in width than the opening between the supplemental post and the opposite permanent post, and adapted to extend on the 35 inside of one permanent door post and to abut the opposite supplemental door post, a longitudinally extending cleat removably secured on the exterior of the supplemental

door post and inside cleats adapted to hold 40 the door from lateral movement.

3. In a car door structure, the combination with the car having the doorway therein, and posts at the side of the door-way, of a door slightly greater in width than the opening 45 between the posts adapted to extend on the inside of one post and to abut the opposite post, a longitudinally extending cleat removably secured on the exterior of one post and inside cleats adapted to hold the door 50 from lateral movement.

4. In a car door structure, the combination with the door-way, of a door for the same, cleats for holding the door in position and a rod pivoted to the top of the door-way 55 and slidably connected to the door at substantially the center thereof.

5. In a car door structure, the combination with the door-way, and the door for the same, of cleats for holding the door in position, a rod pivoted to the top of the door-way 60 having a ring formed on the extremity thereof, a ring secured centrally to the door through which the rod extends, and a hook on the car roof adapted to engage said ring. 65

6. In a car door structure, the combination with the car having an opening therein, and permanent posts at the side thereof, of a supplemental door post, of relatively soft material removably secured to the permanent post, a door adapted to extend across the opening and a cleat adapted to be nailed 70 to the supplemental door post.

THOMAS JOSEPH MACLAUGHLIN
Ottawa, 15th February, 1907.
